UNITED STATES PATENT OFFICE.

FRANCIS G. GALE, OF WATERVILLE, QUEBEC, CANADA.

BEDSTEAD.

982,265.

Specification of Letters Patent. Patented Jan. 24, 1911.

Application filed August 20, 1909. Serial No. 513,791.

To all whom it may concern:

Be it known that I, FRANCIS G. GALE, a subject of the King of Great Britain, residing at Waterville, Province of Quebec, 5 Dominion of Canada, have invented an Improvement in Bedsteads, of which the following description, in connection with the accompanying drawing, is a specification, like characters on the drawing representing 10 like parts.

This invention relates to bed frames of that type where the chills by which the members are united are concealed within the posts or tubular members.

15 In most bedsteads, the tubular members are formed with an open joint, as it is termed, that is, they are made by rolling a sheet of metal into tubular shape with the edges of the sheet abutting but not brazed 20 or otherwise connected together. Where this construction is used in that type of bedstead in which the chills are on the exterior of the parts to be united, said chills act as a means for preventing the joints from 25 opening up. Where the concealed chill construction is adopted, however, the joints of the tubular members are apt to open, thus injuring greatly the appearance of the bed frame.

30 One of the objects of my invention is to provide a bed frame having a concealed chill construction wherein the chills will not only act in usual manner to unite the members forming the bed frame, but will also 35 act to prevent the joints of the tubular members from opening up. With my invention, therefore, it is possible to use the concealed chill feature in a bed frame without the necessity of brazing or soldering or otherwise sealing or closing the seams or joints 40 of the tubular members.

Referring to the drawings wherein I have shown one embodiment of my invention, Figure 1 is an end view of a bedstead made 45 in accordance with my invention; Fig. 2 is a section on the line $x-x$, Fig. 1; Fig. 3 is a section similar to Fig. 2 showing a modification of the invention.

50 My improvements may be embodied in bedstead end frames of a great variety of shapes and designs. That herein shown comprises the usual pillars or posts 3 which are connected at their top by a cross rail or bar 4 and which are also connected by

other curved members 5, 6 having a more or less ornamental configuration. The curved members 5 and 6 lead to a central post 7 and preferably the cross rail 4 extends through said post. The pillars 3 and 4 and also the central post 7 are tubular in 60 construction and are made in the usual manner by bending a piece of sheet metal into tubular shape so that the edges of the sheet abut each other, thus forming a joint or seam 8 which extends longitudinally of the 65 tubular member. In bed frames where the exterior or exposed chill is used, it is not customary to braze or otherwise secure together the edges at the seam 8, but where the chills are poured into the interior of a 70 tubular member made in this way, there would be danger that the joint or seam 8 would open up, thus spoiling the appearance of the bedstead.

My invention is designed to prevent the 75 seam 8 from opening up so that it is possible to use the concealed chill with the tubular member having the open joint.

As herein shown the tubular members are provided with apertures 9 through which 80 the ends of the connecting members 4 and 5 extend as usual, and these members are held in place by chills 10 which are cast within the tubular members so as to surround the ends of the members 4 and 5 and unite 85 them to the tubular members. Each tubular member is also provided with one or more apertures 11 into which a portion of the chill 10 will run as it is being poured, so that when the chill is cold the mass of 90 metal 10 will have a projection or projections 12 extending out through the apertures 11. These apertures 11 are so situated relative to the seam 8 that after the chill is poured and has cooled, the projection or 95 projections 12 will act as means to prevent the seam 8 from opening up. In Fig. 2, for instance, the seam 8 is situated comparatively near the apertures 9 where the members 4 and 5 enter, and the aperture 11 is 100 formed on the other side of the seam so that the projection 12 co-operating with the members 4 and 5 prevents the seam from opening up.

In Fig. 3 I have shown a different construction wherein the tubular member 3 is formed with two apertures 11, one each side of the seam, and when the chill is

5 poured there will be, therefore, two projections 12 which prevent the seam from opening. It will be understood, of course, that this same construction is embodied in the central post 7.

10 In making a bed frame of the shape shown in Fig. 1 the parts will first be assembled and then the bed frame will be turned bottom side up in the mold and the chills at the upper ends of the posts 3 and 7 will be formed, the mold in which the bed frame rests giving shape to the upper or exposed end of the chills. At the bottom of the central post 7 I have shown a 15 chill 15 which connects the ends of the members 5 and 6 to said central post, and in the construction shown, the members 6 are curved to enter the end of the tubular member rather than to enter apertures in the 20 sides thereof as the members 5 do. This special construction is not essential to the invention, however. Where this construction is employed, I propose to provide the tubular member with a partition 16 so that 25 the chill 15 may be poured into the lower end of said tubular member when the bed frame is turned bottom side up. The metal may be poured into the tubular members through the end or through apertures provided for that purpose.

30 From the above it will be seen that with my improvements as herein described the chills are concealed (thus permitting a handsomer bed to be produced than is possible 35 where the chills are exposed) and said chills act not only to connect the tubular members with the other members of the bed frame, but they also lock the edges of the sheet forming the tubular members together so as 40 to prevent the seam from opening up whereby it is possible to use tubular members with open joints instead of the more expensive tubular members in which the seam is brazed or otherwise closed.

45 I wish it understood that my improvement may be embodied in bedsteads of a great

variety of forms and is not limited to the particular design herein shown.

Having fully described my invention, what I claim as new and desire to secure by Letters Patent is:—

1. In a bed frame, the combination with a tubular member formed of sheet metal rolled into tubular shape with its edges abutting and forming an open joint extending longitudinally thereof, said member having two apertures situated on opposite sides of said joint, of a cross member extending into one aperture, and a mass of metal cast into the interior of said tubular member around the 55 end of the cross member and filling the other aperture thereby to prevent the joint from opening up.

2. In a bed frame, the combination with a tubular member having a longitudinally-extending joint or seam, of another member extending into the tubular member through the side thereof on one side of the joint, said tubular member having an aperture on the opposite side of the joint, and a chill within 60 the tubular member surrounding the end of the other member and provided with an integral projection filling the aperture in the tubular member.

3. In a bed frame, the combination with a 75 tubular member having a longitudinally-extending joint or seam, of another member extending into the tubular member through the side thereof, and a chill within the tubular member surrounding the end of the other 80 member, said chill having an interlocking engagement with the tubular member on the opposite side of the joint from that on which said other member is located thereby to prevent the said seam from opening up.

85 In testimony whereof, I have signed my name to this specification, in the presence of two subscribing witnesses.

FRANCIS G. GALE.
